UNITED STATES PATENT OFFICE

ROLLAND T. CASE, OF LA CROSSE, WISCONSIN

CABINET FOR HOLDING SMALL ARTICLES

Application filed November 7, 1929. Serial No. 405,379.

This invention relates to containers and cabinets for holding and rendering conveniently accessible a plurality of articles. While my invention is adapted for wide general use along the lines above indicated, the embodiment illustrated is especially adapted for holding and rendering accessible a plurality of articles, which it is desirable to use successively, such as tooth brushes or toilet accessories.

Authorities on dental hygiene at this time strongly recommend the successive use of a plurality of tooth brushes preferably varying somewhat in shape and form, in order that each brush may be thoroughly dried and stiffened before again being used and in order that the variously shaped teeth and interproximal spaces may be properly engaged and cleansed.

Dentists agree that most people do not brush their teeth for an adequate period of time to thoroughly cleanse the same and to properly stimulate blood circulation in the gums.

It is an object of my present invention to provide a simple but highly efficient cabinet for holding and rendering accessible in rotation, a plurality of articles.

A further object of my invention is to provide a toilet cabinet of the class above described, wherein an article holding element may be progressed step by step each time the door of the cabinet is opened and closed.

Another object is to provide a tooth brush holder or case having a timing element associated therewith which is actuated or rendered operative by a movement of the case or cabinet.

Another object is to provide in a container, an article holder which will receive only a specially constructed article, whereby generally similar articles of another manufacture cannot be held or housed therein.

Still another object is to provide an ornate, compact cabinet for holding a plurality of tooth brushes and associated dental preparations, which will progressively move the brushes into alignment with the doorway each time the door is opened and which will simultaneously actuate or set in operation a timing

element indicating the proper duration of time for brushing the teeth.

These and other objects and advantages of the invention will be apparent from the following description made in connection with the accompanying drawings wherein like reference characters refer to similar parts throughout the several views and wherein,

Fig. 1 is a front elevation of an embodiment of the invention, the door of the cabinet being open to render accessible a tooth brush and to expose for observation the timing element;

Fig. 2 is a vertical section taken longitudinally through my tooth brush cabinet on a diametrically disposed line intersecting the door;

Fig. 3 is a cross section taken on the line 3—3 of Fig. 2; and

Fig. 4 is a cross section taken on the line 4—4 of Fig. 2, showing the means for progressively advancing the brush holding element, the dotted lines indicating the moved positions of the door and other parts.

The embodiment of the invention illustrated, comprises an elongated cylindrical casing, designated as an entirety by the letter C having a perforated base or lower end 5, a perforated top 6, and a relatively narrow doorway 7 extending longitudinally of casing C and, as shown, from top to bottom thereof. A depending U-shaped supporting bracket 8 is spot welded or otherwise rigidly secured to the top 6 of casing C, being mounted substantially centrally of said casing with the opposed vertical sides of the U member substantially in alignment with the doorway 7. A vertical shaft 9 disposed concentrically in casing C is journaled at its upper end in the horizontal base portion of bracket 8, suitable retaining collars 9a being fixed to said shaft at opposite sides of the base of bracket 8. Shaft 9 is journaled at its lower end in the bottom or base 5 of casing C and a suitable friction member 10, such as a resilient spiral section is interposed between a collar 11 fixed adjacent the lower end of shaft 9 and the bottom 5 of the casing, permitting said shaft to be turned in one direction with some degree of friction and pre-

100

venting the shaft from turning in the opposite direction.

An article holding member in the form of a cylinder 12 having a plurality of (as shown 3) inwardly extending channels or compartments 13 is fixed to the medial portion of shaft 9 concentrically thereof. Cylinder 12 may have a bottom 12a provided with an apertured and flanged central portion 12b which is fixed to shaft 9 and the upper end of cylinder 12 is preferably provided with a spanning or closure member 12c having an apertured central portion through which shaft 9 is passed. Each of the channels or compartments 13 is of proper width to nicely accommodate a tooth brush or other article to be held, and means are provided in each channel whereby only an especially designed article or brush may be received. As shown, each of the channels 13 have a centrally disposed outwardly projecting fin 13a extending longitudinally thereof and preferably having inclined and diverging upper and lower edges. A tooth brush B is constructed for the most part in conventional manner, but has the central portion of its handle provided with a longitudinal slot s of greater width than the thickness of fin 13a and as shown in Figs. 1 and 2, the fin will penetrate the slotted portion permitting the handle of the brush to be snugly disposed within the channel. The handle of brush B is provided with an attachment aperture a spaced a short distance from its outer end, and the apertured portion of the brush is adapted to be engaged by a hook 14 conveniently mounted at the upper end of chamber 13. The bristles of the brush will be disposed inwardly and beneath cylinder 12, as clearly shown in Fig. 2.

A door 15 is provided for closing doorway 7 and the said door may have an outwardly bulged compartment 15a provided with a top and bottom wherein a dentifrice or specially constructed vial may be held. Door 15 is hinged along one of its longitudinal edges to casing C and a suitable spring latch or retainer 16 may be fixed to casing C to retain door 15 in closed position. I desire to construct compartment 15a in such manner that only a specially constructed article, such as a dentifrice container or vial may be accommodated therein. With this in view, the compartment is formed narrower than the cross section of the usual tooth paste tube and a spring retaining member 17 having a pair of spaced resilient fingers may be provided, said fingers being of such height or width that they will not engage the relatively short neck of the ordinary dentifrice tube. The dentifrice for use in my cabinet may be put up in a relatively long tube or container D of small diameter, which container has a relatively long neck portion n between the cap and the tube proper, said neck portion

being slightly longer than the width of retaining fingers 17.

Suitable mechanism for progressively revolving the article holding cylinder 12 through a partial revolution each time the door is opened, to bring one of the article holding channels in alignment with the door, is provided, and as illustrated, comprises a disc or ratchet 18 eccentrically fixed to the upper portion of shaft 9 and having on its upper face a series of radially disposed teeth 18a, said teeth having vertical abutment or engagement shoulders and gradually inclined camming surfaces leading to said abutment shoulders. Since three article compartments or channels are provided an equal number of teeth are provided to cause an article to be brought into alignment with the door each time the door is opened. A depending, actuating tooth 19 is fixed to the end of a resilient, actuating arm 20, the inner end of said arm being pivoted on shaft 9 above disc 18. A connecting link 21 is pivoted at one end to the outer end of arm 20 and at its other end is pivotally connected to a small bracket 22 secured adjacent the free vertical edge of door 15. Bracket 22 preferably includes a leaf spring 22a which engages the upper surface of link 21 and yieldingly holds said link downwardly. Arm 20 and link 21 are so proportioned and constructed that the throw of tooth 19 effected by the opening of the door will cause shaft 9 and article holder 12 to be turned through one-third revolution each time the door is opened. In the upper portion of casing C and substantially in alignment with doorway 7 a gravity actuated timing element, such as a minute glass G is mounted, said glass preferably being fixed to an oval-shell member 23, which rigidly carries a horizontal shaft 24 journaled in the parallel and opposing sides of the depending U bracket 8. Shaft 24 is connected for driving with shaft 9 by means of a bevel gear 24a on said shaft meshed with bevel gear 25 secured to the upper extremity of shaft 9. In the embodiment of the invention shown, bevel gears 24a and 25 bear the ratio of two to three in order that shaft 24 and glass G may be revolved through 180° each time shaft 9 is turned through 120°. In this manner, the gravity actuated timing element will be reversed each time the door is opened, causing the sand or other time indicating material to be disposed at the upper end of the glass each time the door is opened.

Suitable means is provided for conveniently mounting casing C on a wall or supporting surface and as shown a bracket B is provided having small outwardly projecting sockets 26 wherein depending tongues 27 rigidly fixed to the rear of casing C are secured. The cylinders C may also be provided with a series of supporting lugs 28 on the base thereof adapted to hold the bottom of the cylinder in

spaced relation to a supporting surface to permit circulation of air therethrough.

Operation.

The operation of my improved device may be briefly described as follows:—
When the door 15 is swung to full open position, the operating arm 20 engaging the ratchet disc 18 by means of tooth 19 will move shaft 9 and article holding cylinder 12 through 120°, bringing one of the article holding channels or compartments in juxtaposition and in registration with the door opening 7. The article may then be conveniently removed. In the embodiment of the invention shown, the upper extremity of tooth brush B may be pressed inwardly above hook 14 by the index finger, causing the lower portion of the brush to swing outwardly through the doorway where it may be conveniently grasped and removed from the container. The partial revolution of shaft 9 due to the three to two gear ratio between shafts 9 and 24 swings the minute glass G through 180° during the 120° movement of shaft 9. Thus, the timing element is actuated or set in movement by the opening of the door. A person owning the cabinet will then brush his teeth during the time required for the sand or other material in glass G to fall to the lower portion of the glass.

The closing of door 15 causes inward movement of resilient arm 20, the tooth 19 riding over the inclined upper surface of ratchet disc 18, until said tooth drops into the next ratchet tooth or abutment surface 18a. The resiliency of arm 20 and connecting link 21 and the influence of leaf spring 22a impel the actuating tooth 19 in a downward direction during the movement of said parts. The closing of the door thus resets the device for the next progression.

The tooth brushes or other articles in the manner above described are moved successively into alinement with the doorway each time the door is opened and may be easily removed from the cabinet, used and again hung in the appropriate holding chamber by merely causing the appropriate hook 14 to engage the apertured portion A at the outer end of the handle, gravity causing the brush to swing inwardly with the fin 13a of the holding chamber penetrating the slotted portion S of the brush handle.

It will be obvious that brushes constructed in conventional manner cannot be disposed within my holding chambers due to interposition of the fin 13a. The slotting of the brush handle in addition to forming a brush handle of complementary shape to the holding chamber adds a resiliency and flexibility to the brush which is of considerable advantage in the proper brushing of the teeth.

It will be seen that tubes and tooth paste containers of conventional type cannot be

housed within my compartment 15a afforded by the door 15 due to the shape of said compartment and also due to the fact that the spring holding elements 17 are of such width that they cannot engage the short necks of tooth paste tubes now in use.

From the foregoing description it will be apparent that my tooth brush holder will accommodate only brushes and other articles especially constructed for insertion therein, thus enabling the manufacturer of the specially constructed tooth brush to obtain all new orders for tooth brushes and paste for use with this cabinet.

The brushes in the cabinet will automatically be successively selected and the bristles will have time to dry before the brush is again moved to alinement with the doorway.

It will, of course, be understood that various changes may be made in the form, details, arrangement and proportions of the parts without departing from the scope of applicant's invention, and likewise, that while the embodiment of the invention illustrated is a tooth brush and accessory cabinet, that the invention is applicable for housing, holding and successively selecting for removal, articles of all kinds.

What is claimed is:

1. In a cabinet, a casing having a doorway in a portion thereof and a door hinged to said doorway, a shaft rotatively mounted in said casing, a holding member fixed to said shaft and having a series of circumferentially arranged article holding elements a ratchet disc fixed to said shaft and having a plurality of ratchet teeth, the number of said teeth being similar to the number of said article holding elements, an actuating arm loosely mounted on said shaft at its inner end and having a projecting tooth at its outer end for engagement with said ratchet teeth, and a link connecting said arm with said door, whereby said article holding elements will be successively brought into alinement with said doorway by the opening and closing of said door.

2. In an article holder, a holding element mounted for progressive movement, a time determining element associated with said holding element, and means dependent upon the movement of said holding element for rendering said timing element operative when said holding element is moved through a predetermined distance.

3. In an article holder, a holding member mounted for rotary movement and a gravity actuated timing element associated with said article holder, connections between said article holder and timing element for reversing said timing element each time said holding member is turned through a predetermined distance.

4. In an article holder, a holding element mounted for rotary movement, a gravity actuated timing element mounted for rotary

movement on an axis extending at right angles to the axis of said holding element and driving connections between said holding element and said timing element for rotating said timing element through 180° each time said holding element is turned through a predetermined distance.

5. In an article holder, a vertical shaft rotatively mounted, an article holder fixed to said shaft, a gravity actuated timing element rotatively mounted on a horizontal axis and having gear connection with said vertical shaft for reversing the position of said timing element each time said holding member is swung through a predetermined distance.

10. In an article holding cabinet, a casing having a doorway therein, a holding member mounted for movement within said casing having a series of spaced article holding elements, an actuating mechanism for progressively moving said holding member to successively bring said article holding elements into alignment with said doorway, a gravity actuated timing element rotatively mounted, and driving connections between said timing element and said holding member for swinging said timing element through 180° each time one of said holding elements move into alignment with said doorway.

15. In a cabinet, a casing having a doorway, a door hinged to an edge of said doorway, a holding member rotatably mounted within said casing upon an axis extending substantially parallel with the hinge of said door, a series of circumferentially spaced holding elements mounted on said holding member and actuating mechanism connected with said door and said holding member for progressively moving said holding member to align one of said holding elements with said doorway each time said door is opened and closed.

20. In a cabinet, a casing having a doorway, a door hinged to one edge of said doorway, a rotatable holding member mounted in said casing and rotatable upon an axis extending substantially parallel with the hinge axis of said door, a series of circumferentially arranged article-holding elements connected with said holding member, a swingable operating arm mounted concentrically with the axis of said holding member, the outer end of said arm being engageable with said holding member for movement in one direction and a connection between said arm and said door whereby said article-holding member may be progressively moved upon the opening and closing of said door.

25. In a cabinet, a casing having a pair of opposed ends and a peripheral wall provided with an aperture therein, a movable holding member the ends of which are mounted between said casing ends, said holding member having a series of spaced holding elements

disposed longitudinally thereof, a reciprocable element pivotally mounted on said casing and swingable on an axis extending longitudinally of the peripheral wall of said casing and actuating mechanism connected with said reciprocable element and said holding member for progressively moving said holding member to align one of said holding elements with said aperture in the peripheral wall of said casing each time said reciprocable element is reciprocated.

30. In a cabinet, a casing having a pair of opposed ends and a peripheral wall provided with an aperture therein, a holding member rotatably mounted between the ends of said casing and having a series of circumferentially spaced holding elements, a reciprocable element hinged to the peripheral wall of said casing adjacent said aperture and swingable on an axis parallel with the axis of said holding member and actuating mechanism connected with said reciprocable element and said holding member for progressively moving said holding member to align one of said holding elements with said aperture each time said reciprocable element is reciprocated.

35. In an article holder, the combination with an article having a specially constructed slot in a portion thereof, a receiving compartment having side walls, a rear wall and an open forward side, said side walls being shaped to closely conform to a substantial portion of the contour of said article, and an outwardly projecting member mounted on the rear wall of said compartment and of similar cross sectional shape to the shape of said specially constructed slot and adapted to be accommodated by said slot whereby articles of any other construction will be excluded from said compartment.

40. In an article holder, the combination with an article having a specially constructed elongated slot in a portion thereof, a receiving compartment having side walls, a rear wall and an open forward side, said side walls being shaped to closely conform to a substantial portion of the contour of said article whereby articles of a different contour will be excluded and an outwardly projecting fin or rib mounted on the rear wall of said compartment and of similar cross sectional shape to the shape of said specially constructed slot and adapted to be accommodated by said slot whereby articles of any other construction will be excluded from said compartment.

45. In an article holder, the combination with an article having an attachment element adjacent one end and having a specially constructed slot in a portion thereof, a receiving compartment having side walls, a rear wall and an open forward side, said side walls being shaped to closely conform to a substantial portion of the contour of said article, said compartment having an element for en-

gagement with the attachment element of said article to support said article and having an outwardly projecting member secured to the rear wall of said compartment and of similar cross sectional shape to the shape of said specially constructed slot and adapted to be accommodated by said slot whereby articles of any other construction will be excluded from said compartment.

5 10 In testimony whereof I affix my signature.
